BELT LOADING MACHINE

Joseph E. Turnock, Riverton, N. J., and Edgar M. Cloeren, Jr., Philadelphia, Pa.

Application December 15, 1939, Serial No. 309,412

5 Claims. (Cl. 86—48)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to a belt loading machine intended for loading cartridges into interfitted links to form a cartridge belt of the disintegrating link type.

The purpose of the invention is to provide an efficient and reliable belt loading machine in which cartridges are positively supplied to a rammer which advances them into links carried by an endless belt.

A further object of the invention is to provide an improved means for selectively presenting ball and tracer cartridges to the rammer whereby they may be loaded in predetermined sequence into the belt.

The specific nature of the invention as well as other objects and advantages thereof will clearly appear from a description of a preferred embodiment as shown in the accompanying drawings in which:

Fig. 1 is a plan view of the belt loading machine with the parts in position to load a cartridge;

Fig. 2 is a longitudinal sectional view on the line 2—2 of Fig. 1;

Figs. 3, 4 and 5 are sectional views on the respective lines of Fig. 2.

The machine comprises a housing A having an upper bed plate 5 on which a magazine B is secured by means of dowel pins 6. The magazine comprises a plate 7 resting on the bed plate and having a centrally located, elongated passage 8 for receiving a cartridge C which rests on a wear plate 9 in the bed plate 5. A rectangular feed box 10 formed on the upper side of the plate 7 includes a central, longitudinally extending partition 11 to provide a pair of vertical feed channels 12—12 for the cartridges. The partition is spaced from the plate 7 to provide a horizontal feed channel 13 which establishes communication from the vertical channels 12—12 to the passage 8. A chute 14 fitting on the upper edge of the feed box 10 and secured by bolts 15 and wing nuts 16 is provided with a pair of channels 17—17 leading to the channels 12—12 and intended to supply cartridges of different types, for example ball and tracer.

Referring to Figs. 1 and 2 the mechanism for advancing a cartridge from the passage 8 of the magazine comprises a rammer 18 which is threaded in a crosshead 19 and is provided with

adjusting collar 20. The crosshead is mounted for reciprocation in guideways 21 of the housing A and carries a depending stud 22 having a cam follower 23 on its lower end. The cam follower rides in a cam groove 24 formed in a cylindrical roller 25 which is disposed within the housing and carried by a shaft 26 mounted in the housing. The cam roller may be driven either manually or by means of a motor.

The end of the magazine adjacent the crosshead is formed with a pair of spaced bracket arms 10a—10a for mounting a shaft 27. A ratchet crank 28 loose on the shaft is confined against one of the arms by a ratchet wheel 29 whose hub is fixed to the shaft by a pin 30. A pawl 31 pivotally carried by the crank is held in driving engagement with the ratchet wheel by means of a spring 32. A link 33 pivotally mounted on a pin 34 on the crank is connected by means of a turnbuckle 35 to a link 36 which is formed with an elongated slot 37. The slotted end of the link 36 is disposed between the arms of a yoke 38 threaded in the crosshead and a pin 39 carried by the yoke extends through the slot and pivotally supports the link.

A pair of cylindrical cam wheels 40 and 41 are mounted on the ends of the shaft 27 and are secured thereon respectively by pins 42 and 43. The outer face of the wheel 40 is provided marginally with a plurality of spaced lobes 44 and with a dwell 45 produced by omitting one lobe. The outer face of the wheel 41 is provided marginally with a single cam lobe 46 which corresponds angularly to the dwell 45 of cam wheel 40.

A pair of similar levers 47—47 disposed on opposite sides of the feed box and each mounted on the magazine by a pivot pin 48 are each provided on one end with an upright pin 49 carrying a roller 50 for engaging the outer lobed face of a cam wheel. The opposite end of each lever is formed into a fork 51 which engages a pin 52 on a feed slide 53. Each feed slide is mounted in a casing 54 secured to the magazine and the pin 52 extends upwardly through a slot 55 in the cover of the casing. The inner end of the feed slide normally extends through an opening 56 in the side wall of the feed box to engage a cartridge and move it across the horizontal feed channel 13. The lever is normally held with its roller 50 against the cam wheel by means of a spring 57 which connects the pin 52 with a pin 58 on the chute.

Referring to Figs. 1 and 5 the housing A has a laterally extending portion 59 for carrying an

endless chain 60 whose movement is on a path perpendicular to the path of movement of the rammer. The belt is trained around a sprocket 61 at the outer end of the portion 59 and a sprocket 62 disposed within the housing A. The sprocket 61 is fixed on a shaft 63 which is mounted in opposed bearing blocks 64 that are adjustably carried in the portion 59 and each held in place by opposed screws 65-65. The sprocket 62 is fixed on a shaft 66 which is mounted in bearings 67 and 68 (Figs. 2 and 4) forming part of or fixed to the housing A.

The upper reach of the chain is supported by a channeled guideway 69 which is fixed to the portion 59 of the housing between the sprockets. The chain is provided on its outer side with spaced, transversely disposed lugs 70 for positioning and holding metallic links D of the disintegrating belt type.

The links are held fed to the chain and are held against lateral displacement by the guideway 69. A link stop 71 (Figs. 1 and 2) mounted on the housing above the sprocket 62 is adapted to restrain the links against endwise movement during insertion of a cartridge and it includes an arm 72 overhanging the link belt to restrain the links against upward displacement. The stop 71 is provided with an opening 73 for accommodating the bullet end of the cartridge.

A link stripper 74 (Fig. 5) in the form of a blade is attached to the housing A and projects into the opening 75 of the housing to engage a link and insure its removal from the chain.

A finger 76 attached to the housing adjacent the link stripper 74 also projects into the opening and serves to support the rear end of the cartridge.

When a cartridge is loaded into the link belt its rear portion is supported on a roller 77 (Figs. 2 and 5) which is fixed to the shaft 66. The roller is formed with longitudinally extending recesses 78 for receiving the cartridge and it is also formed with an annular groove 79 for accommodating the finger 76.

The shaft 66 carries a gear wheel 80 which meshes with a pinion 81 on one end of a countershaft 82 mounted in the bearing 68. A Geneva wheel 83 is carried on the other end of the countershaft and is driven by a conventional pin wheel 84 on shaft 26 to afford intermittent movement. The pin wheel includes the usual pin 85 and cam 86.

In operation the cam roller 25 reciprocates the rammer 18 and imparts angular movement to the ratchet crank 28 to actuate the ratchet wheel 29 through pawl 31 and intermittently rotate the shaft 27. The cam wheels 40 and 41 on shaft 27 control predetermined sequence of actuation of the levers 47-47 which in turn control the predetermined sequence of movement of cartridges from the pair of vertical feed channels 12-12. The cartridges are therefore presented in a predetermined order in the passage 8 from which they are to be advanced by the rammer 18 and loaded into the metallic links D.

The shaft 26 of the cam roller 25 acting through the Geneva movement 83-86 intermittently drives the countershaft 82 and the shaft 66. The chain 60 and the roller 77 are thereby intermittently actuated to advance the cartridge that has been loaded into the links D of the chain and to clear the way for loading of the next round.

We claim:

1. In a cartridge feeding mechanism, a reciprocable cartridge advancing rammer, a shaft adjacent the rammer, a ratchet wheel on the shaft, a ratchet crank loose on the shaft, a pawl on the ratchet crank for driving the ratchet wheel, linkage between the ratchet crank and the rammer, a pair of cam wheels on the shaft and means controlled by the cam wheels and controlling a predetermined sequence of presentation of cartridges to the rammer.

2. In a machine for loading a link belt, a housing, a reciprocally mounted rammer carried by the housing, a cam roller for reciprocating the rammer, means for supplying cartridges to the rammer, an endless chain mounted for movement perpendicularly to the rammer, and adapted to carry a metallic link belt, a roller having recesses for receiving a cartridge advanced by the rammer, a shaft for driving both the roller and the chain, a countershaft adjacent the shaft, gearing between the shaft and countershaft, a Geneva wheel on the countershaft, a pin wheel driven by the cam roller and intermittently driving the Geneva wheel.

3. In a machine for loading a link belt, a housing, a reciprocally mounted rammer carried by the housing, means for reciprocating the rammer, means for supplying cartridges to the rammer, an endless chain mounted for movement perpendicularly to the rammer and adapted to carry a metallic link belt, a roller having recesses for receiving a cartridge advanced by the rammer, a shaft for driving both the roller and the chain, and means for intermittently driving said shaft from the means for reciprocating the rammer.

4. In a machine for loading a link belt, a housing, a reciprocally mounted rammer carried by the housing, means for reciprocating the rammer, means for supplying cartridges to the rammer, an endless chain mounted for movement perpendicularly to the rammer, means on the chain for positioning a metallic link belt and means for intermittently driving the endless chain from the means for reciprocating the rammer.

5. In a machine for loading a link belt, a housing, a rammer reciprocally carried by the housing, means for reciprocating the rammer, means for supplying cartridges to the rammer, an endless chain mounted for movement perpendicularly to the rammer, means on the chain for positioning a metallic link belt, and means for intermittently driving the endless chain.
